UNITED STATES PATENT OFFICE

FRIEDRICH DÖPPENSCHMITT, OF PFORZHEIM, GERMANY

FLEXIBLE STRUCTURE

Application filed January 31, 1928, Serial No. 250,756, and in Germany April 19, 1927.

The present invention has reference to improvements in flexible bands, especially for the purposes of personal adornment, such as wrist watch straps, bracelets, anklets, and the like, and relates more particularly to a structure of this general character formed of a longitudinal one-piece base member and a plurality of relatively narrow cross-members, each one of which is endwise hooked over the base member, the individual cross members themselves not being interconnected in any manner.

My invention will readily be understood from a detailed description in connection with the accompanying drawings, in which Fig. 1 is a front elevation of a portion of the new band structure; Fig. 2 is a cross-section, on an enlarged scale, on line 2—2 of Fig. 1; Fig. 3 is a rear view of the band, showing a modified construction; Fig. 4 is a cross-section therethrough on line 4—4 of Fig. 3, on an enlarged scale; Fig. 5 is a front view, and Fig. 5a an edge view of a cross member blank before edge-rounding; Fig. 6 shows the complete bracelet in open position, and Fig. 8 the same in closed position; Fig. 7 is an edge view of the keeper box of the bracelet, and Fig. 9 is a cross-section showing another slight modification.

The base member, which may be an elastic strip or band 1 of gold, silver, composition, or other sheet stock, or of metal mesh fabric 2, to wit, milanaise fabric, (Fig. 3), serves as support for the thin cross-members 3, preferably also of metal but not necessarily of elastic character, which are arranged on the supporting strip 1 in close contiguous relation to form a practically uninterrupted covering or armor therefor. The individual members 3 have turned-over or hooked clamping edges or tongues 4 and are arranged on the band member 1 by simply being placed on the outer side of the band and then by suitable mechanical means their ends are bent in hooked formation over the respective longitudinal edges of the band 1, as clearly shown in the drawing.

To strengthen the structure generally and enhance its elasticity, or afford a better purchase for the members 3 and a closer fit

thereof, there may be interposed between the members 3 and the support band one or more stiffening or filling members 5, of which only one is shown in Figs. 1 and 2, which may be of spring steel, metal fabric, textile fabric, celluloid, or the like, depending upon the effect desired.

In order to ensure to the structure the necessary flexibility on being bent, the side edges 6 of the hooked end portions 4 are set back to a relatively slight extent, as shown in a somewhat exaggerated manner in Fig. 5, so that, on flexure of the band, the facing beaded edges of adjacent members 3 contact only after the limit of flexing movement has been reached.

The invention has the important advantage that the individual members 3, which form the outer show surface of the structure, may be made of very thin sheet metal or other material, but, since they are backed by a relatively stiff, strong supporting member, they are not apt to become deformed or damaged in use. They may be superficially ornamented, for instance carved or jewelled in any desired manner, and they may be of any desired body-conformation, for instance embossed or buckled as shown by way of example at 7 in Fig. 9. The hooked or beaded top and bottom edges impart to the finished article a solid, rich appearance and add greatly to the wearing comfort.

For lockingly uniting the band ends, the inherent elasticity of the annularly bent structure is utilized, as shown in Figs. 6, 7 and 8. At the one end of the band there is provided a keeper box 8 with the usual slot 9, and from the other band end extends the catch 10. For locking the bracelet, or the like, it is forcibly distorted out of its annular plane as shown in Fig. 6, is then closed with the catch 10 engaging in the slot 9, and is then let go, when the resiliency of the structure will cause the catch to be securely retained in the keeper box (Fig. 8) against unintentional opening.

What I claim is:—

1. A thin flexible structure of the character described comprising a flexible supporting band having opposite longitudinal edges, 100

- and an armor covering the outer side of said supporting band and consisting of comparatively long and narrow individual thin metal cross members, each reduced in width at their ends with respect to the width of their body portions, and extending in the direction of their length transversely of the outer face of the supporting band and having their ends bent over into engagement with the longitudinal edges of said supporting band and rebent backwardly toward the opposite side of said band with their transverse extremities impinging against said side of the band.
- 15 2. In a flexible structure of the character set forth, in combination, a flexible supporting member, a plurality of relatively narrow cross members endwise hooked over said supporting member in close formation, and 20 stiffening means interposed between said supporting member and said cross members.
3. In a flexible structure of the character set forth, in combination, a flexible supporting member, and locking means comprising 25 a keeper box at one end of the supporting member having a keeper chamber between its longitudinal center and one longitudinal edge of said member open at its side toward the other longitudinal edge of said member 30 and communicating at said side with an entrance and exit slot opening through the end of the supporting member between its longitudinal center and the latter-named longitudinal edge of the supporting member, and 35 a catch at the other end of the supporting member having a laterally projecting hook insertable into and removable from the keeper member through said slot and engageable with and disengageable from the 40 keeper chamber by relatively lateral movements of the ends of the supporting member out of the normal plane of the latter.

In testimony whereof I affix my signature.

FRIEDRICH DÖPPENSCHMITT.
